11 Claims. (Cl. 53—76)

Our invention relates to bread loaf packaging machines, and more particularly to a machine for packaging a sliced loaf of bread.

More specifically our invention relates to a machine for packaging a sliced loaf of bread in such a way that the package can be easily opened and reclosed at one end thereof when desired, for the removal of slices from the package, and reclosure of the package, and even for replacement of some of the removed slices in the package and reclosure thereof, should this be desired. In order to provide such a package, the machine is designed to fold and seal the wrapper at one end of the package in the usual manner and to overlap the wrapping material extending around the loaf and seal it on the bottom side of the loaf in the usual manner, but to avoid sealing the other end of the package at the other end of the loaf, the breaking of which seal results in the tearing of the wrapper so that it can no longer be tightly closed, and provide a removable and replaceable closure at that end of the package, by contracting the extended wrapping material at that end of the loaf so that a tie can be applied thereto, preferably by gathering said extended wrapping material and twisting it on itself, and tying the twisted wrapper closely adjacent the loaf, so as to make the package air tight, with a tie that is capable of being repeatedly twisted into package closing position and untwisted to open the package.

The wrapping of sliced bread has resulted in considerable difficulty being encountered in opening and reclosing the package by the user of the sliced bread, contained in the usual package in which the sliced bread is put up for selling, which is ordinarily a wrapper of heat sealing material, such as paraffin or waxed paper, thermoplastic sheet material, or other transparent heat sealing wrapping material. In the ordinary manner of preparing the package, the sheet material, such as waxed paper, or other thermoplastic transparent sheet material, that is heat sealed, is folded over at the ends of the loaf and the overlapped plies sealed so as to completely seal and enclose the package at the ends of the loaf, and the package is provided with a longitudinal overlap along the bottom of the loaf to provide an overlapped seam, at the bottom of the loaf, which is also heat sealed. When such a package is opened by breaking the seal at one end thereof and some of the slices of the bread removed, it is impossible, unless a very large amount of the bread is removed, to again close up the package so as to prevent drying out of the slices of bread that remain in the package, because of damage to the wrapper or because, even if the wrapper is not torn, there is insufficient material at the opened end of the package to tightly close it again manually.

Our improved machine provides a package for a sliced loaf of bread that will permit closure of the package that has once been opened, so that any slices of bread that may have been removed, that it may be desired to replace, can be replaced therein, and which will be capable of being closed air tight, or substantially air tight, even when only a few slices have been removed, or if no slices have been removed, it being possible to open one end thereof and reclose the package to its original condition

under any and all conditions. While sliced bread has been packaged in plastic film bags that had such a removable and replaceable closure, this had to be done manually and the sliced bread in the package became disarranged because it was loosely positioned in the bag.

Our improved packaging machine provides a sliced bread loaf package that has a wrapper of heat sealing material that is wrapped transversely around the loaf tightly so that the wrapper conforms to the shape of the loaf and which has its longitudinal edges overlapped and the overlapping portions sealed to each other with the wrapper closely conforming to the shape of the loaf, and in which one end of the wrapping material is folded on itself and sealed in position against one end of the loaf, while the other end of the wrapper extends far enough beyond the other end of the loaf that it is gathered together and twisted and a tie placed around the same so as to tightly close that end of the package, which tie can be removed so that access can be had to the interior 10 of the wrapper to remove any number of slices of bread therefrom, and either replace some of them or merely replace the heel on the loaf, or replace none of the removed bread, and again close the package by means of the tie member by manually twisting the wrapping material 15 and replacing the tie member tightly around the twisted wrapper closely adjacent the end of the loaf, so that the slices will all stand up in the package in their usual side by side, face to face relationship in longitudinal alignment with each other. This is possible because the wrapper corresponds in shape to the corresponding portion of the loaf around which it was wrapped, whereby each part of the package will fit closely the slice 20 that was located in that part of the package at the time the package was formed. As the machine twists the extended portion of the wrapper tightly to a point closely adjacent the end of the loaf on which the package is not folded and sealed, the wrapper is tightened closely around the sliced loaf at that end of the package and the sliced loaf will stand up in the package during handling from 25 the time it leaves the packaging machine until received by the purchaser and transported to the place of use thereof.

It is a purpose of our invention to provide a bread loaf packaging machine that is provided with means for wrapping a length of wrapping material wider than the length of the loaf around the loaf with the ends of the material overlapping under the loaf and with the overlapped wrapping material extending beyond both ends of the loaf, means for folding the extended wrapping material against one end of the loaf and sealing the folded material at that end of the loaf, as well as means for sealing the overlapped ends of the wrapping material on the under side of the loaf, the wrapping material extending from the end of the loaf that is not sealed, being longer than that at the sealed end of the package, and means being provided for gathering together and twisting on itself this extended wrapping material and applying a tie member thereto, closely adjacent the other end of the loaf.

In our machine, the folding means and sealing means 45 for closing the bottom and the one end of the package are of the usual character, and the extended unsealed end of the wrapping material is acted on to begin the gathering operation, during the folding and sealing operations of the machine for the end and bottom of the package. 50 In folding the material at one end of the package an arm is ordinarily utilized for doing some of the folding, which arm also holds one end of the loaf so that the slices will not become separated. A similar arm, modified for the purposes of this machine, is provided for engagement with the other end of the loaf to also hold up that end of the loaf and prevent the slices from becoming separated. This last mentioned arm is utilized for directing the ex- 55 60 65 70

tended wrapping material that is to be twisted, into guideways, that are provided for gradually bringing the tubular extended portion of the wrapper together into a substantially flattened tubular form, for presentation to the twisting mechanism.

Our invention further includes means for maintaining the sliced loaf in position with all of the slices of the loaf in face to face engagement with each other from the beginning of the wrapping operation until the twisting of the extended portion of the wrapper is done, said means comprising a guide member engaging the sealed end of the package and guiding means for the other end of the package, comprising a pair of guide rods that engage the extended end of the wrapper in close adjacency to the end of the loaf from which the wrapper extends, to hold said wrapper closely against said end of the loaf and to support the sliced loaf between these guide rods and the guide member that engages the sealed end of the loaf. The guide members that are at the extending end of the wrapper, are of such a character that the same engage the extended portion of the wrapping material at spaced points, said guiding means comprising parallel guide members that are parallel to the above referred to guide rods, and are located laterally outwardly from the guide rods. Said guiding means comprises upper and lower guide members that gradually converge toward the twisting mechanism, so as to bring the wrapping material gradually together in a flattened form, with the upper portion of the tubular extension of the wrapper being brought into close adjacency with the lower portion thereof.

In a bread wrapping machine it is customary to provide pusher members that push the loaves during the wrapping and sealing operations over a table, or tables, and these pusher members are utilized for moving the loaf in its partially wrapped condition, from the wrapping station at one end of the machine to the twisting station, where the twisting means is located. Due to the flexibility of the material used for wrapping the package and the fact that this material does not contain any bread at the extended end thereof, and frictionally engages with the guide members as it slides along the same, the tendency is for the extended portion of the wrapper to lag behind the loaf and not travel in longitudinal alignment with the loaf around which the major portion of the wrapper extends. As it is necessary that this extended portion of the wrapper be in substantially central axial alignment with the wrapped loaf, when the twisting operation is performed, in order that the twisted wrapper be properly formed and that it be located in the middle of the end of the loaf that is provided with the detachable closure means, means is provided for lining up the extended portion of the wrapper with the remainder thereof that is around the loaf, comprising grooved friction rollers, in the grooves of which the guide members for the wrapper extend, which friction rollers rotate at a higher peripheral speed than the forward speed of the loaf, due to the action of the pusher members, whereby the alignment of the extended portion of the wrapper with the loaf is restored. In order that this relationship between the extended portion of the wrapper and the loaf be maintained, rollers are provided between the friction rollers and the twisting mechanism for conveying the extended portion of the wrapper into the twisting mechanism and flattening the wrapper in a horizontal plane.

Our invention further comprises twisting mechanism for the extended end of the wrapper, comprising a pair of jaws, elongated lengthwise of the machine, that are mounted for rotation about an axis transverse to the length thereof, said jaws being provided with inflatable members for clamping the extended wrapping material between the same, and means for rotating said jaws about said axis a plurality of times in order to provide the desired twist in the extended portion of the wrapping material, said means for rotating the jaws being provided with a suitable controlling mechanism whereby the twist-

ing operation is not begun until the loaf is in proper position, with the extended wrapping material between the jaws, and the jaws have been inflated to close the same and clamp the wrapping material therebetween, the means for controlling the rotation of the jaws being of such a character that the rotation of the jaws will be halted with the jaws in such a position that the same will have the opening between the jaws in alignment with the guiding means for the extended wrapping material leading to the twisting mechanism.

Our invention further includes means for applying a tie member to the twisted wrapper that extends from the loaf, after the twisting operation has been completed, comprising means for feeding tie material, which is in the form of a continuous length, onto a pair of spaced supporting members providing a gap between the same, cutting off a length of said material after it has reached this position, and then applying this tie member to the twisted extended portion of the wrapper. The twisted extended portion of the wrapper itself is used for bending the tie member therearound in a U-form with the legs of the U extended upwardly from the twisted end of the wrapper. In order to accomplish this, the supporting means for the cut-off length of tie member is mounted to move between a position below the axis of rotation of the twisting member into a position above the axis of rotation thereof and is provided with a recessed die member movable therewith cooperative with said twisted wrapper, and the operation thereof is controlled so that this movement takes place after the twisting operation has been completed.

Means is provided in cooperation with the supporting means for the tie members, and located above the upper position thereof, for twisting the upwardly extending legs of the tie member about each other so as to tightly secure the tie member around the twisted wrapper. The tie member is preferably made up of a flat band of plastic material in which a plurality of substantially parallel ductile wires are embedded, and the wrapper is preferably made of a film that will easily twist into the form desired, such as polyethylene or polypropylene. Any highly flexible film material is suitable for wrapping the loaf.

It is a further purpose of our invention to provide means for controlling the sequence of operations of the wrapper twisting, tie applying and tie twisting means comprising a plurality of circuit controlling cams, which are continuously rotated, but which are inoperative to supply electrical energy to the controlling circuits that operate these various devices in sequence until the wrapped loaf has reached the location at which the twisting and tying operations are carried out, the controlling means comprising switching means engaged by the wrapped loaf, when it reaches the above referred to location, and switching means actuated by one of the cams, both of which switching means have to be closed before the other cams will be effective to energize the various controlling circuits for carrying out the sequence of operations in their proper order.

Other objects and advantages of our invention will appear as the description of the drawings proceeds. We desire to have it understood, however, that we do not intend to limit ourselves to the particular details shown or described, except as defined by the claims.

In the drawings:

FIG. 1 is a top plan view partly broken away of our improved loaf packaging machine.

FIG. 2 is a top plan view of the portion of the machine at which the wrapper twisting and tying operations are carried out and adjacent portions thereof, on an enlarged scale, the loaf conveying means being omitted.

FIG. 3 is an enlarged fragmentary view partly in elevation and partly in vertical section taken on the line 3—3 of FIG. 2.

FIG. 4 is an enlarged fragmentary vertical sectional view, partly in elevation, taken on the line 4—4 of FIG. 2.

FIG. 5 is a fragmentary view partly in vertical section and partly in elevation, taken on the line 5—5 of FIG. 1, on an enlarged scale, showing the loaf supporting means in down position in full lines and in elevated position in dotted lines.

FIG. 6 is a fragmentary section taken on the line 6—6 of FIG. 1 on an enlarged scale.

FIG. 7 is a fragmentary section, on an enlarged scale, taken on the line 7—7 of FIG. 1, showing the loaf supporting means in full lines in down position and in dotted lines in elevated position.

FIG. 8 is a fragmentary view on an enlarged scale, partly broken away, taken on the line 8—8 of FIG. 2.

FIG. 9 is a fragmentary view, partly in elevation and partly in vertical section, on an enlarged scale, taken on the line 9—9 of FIG. 2.

FIG. 10 is a fragmentary enlarged detail view partly in elevation and partly in vertical section taken on the line 10—10 of FIG. 2.

FIG. 11 is a fragmentary view partly in elevation and partly in vertical section, on a slightly enlarged scale, taken on the line 11—11 of FIG. 2.

FIG. 12 is a fragmentary elevational view on an enlarged scale, taken on the line 12—12 of FIG. 2.

FIG. 13 is a fragmentary enlarged side elevational view taken on the line 13—13 of FIG. 1.

FIG. 14 is a fragmentary view partly in vertical section and partly in elevation taken on the line 14—14 of FIG. 13.

FIG. 15 is a view partly in elevation and partly in vertical section of the twisting mechanism, showing the clamping jaws in uninflated condition.

FIG. 16 is a section taken on the line 16—16 of FIG. 15.

FIG. 17 is a view similar to FIG. 15, showing the clamping jaws in inflated condition.

FIG. 18 is a section taken on the line 18—18 of FIG. 17.

FIG. 19 is a fragmentary perspective view showing the first step in folding the folded and sealed end of the wrapper and the corresponding position of the holding and guiding arm for the open end of the wrapper.

FIG. 20 is a fragmentary perspective view of the open end of the wrapper prior to engagement with the guiding means therefor.

FIG. 21 is a similar view, as viewed from the other end of the wrapper, and showing the second folding operation at the folded end of the wrapper.

FIG. 22 is a view similar to FIG. 20, but showing a further advanced position of the parts.

FIG. 23 is a view similar to FIG. 21, showing the partially folded wrapper approaching the guide member with which the folded end of the package engages.

FIG. 24 is a fragmentary perspective view of the folded and sealed end of the package after the folding and sealing has been completed.

FIG. 25 is a similar view of the twisted and tied end of the package after the packaging operation has been completed.

FIG. 26 is a fragmentary enlarged detail view taken on the line 26—26 of FIG. 2.

FIG. 27 is a similar view taken on the line 27—27 of FIG. 2.

FIG. 28 is a fragmentary horizontal sectional view on an enlarged scale through one of the guide plates.

FIG. 29 is a fragmentary detail view of the tie supporting slide in depressed position.

FIG. 30 is a similar view thereof in raised position.

FIG. 31 is a fragmentary plan view of the tie feeding means.

FIG. 32 is a fragmentary sectional view on an enlarged scale, taken on the line 32—32 of FIG. 2.

FIG. 33 is a fragmentary detail view partly in section on the line 33—33 of FIG. 30.

FIG. 34 is an enlarged sectional view taken on the line

34—34 of FIG. 1, certain portions of the switch operating mechanism being shown somewhat diagrammatically.

FIG. 35 is a diagrammatic longitudinal sectional view through a double acting solenoid valve.

FIG. 36 is a diagram of the operating circuit for the wrapper clamping and twisting means and the tie feeding and twisting means, and

FIG. 37 is a fragmentary detail view of the tie twisting member taken on the line 37—37 of FIG. 3.

Referring in detail to the drawings, our improved machine is shown as being provided with a frame 30 having at one end thereof the frame members 31 and 32. Mounted on the frame is a table having the portions 33 and 34 which are in longitudinal and horizontal alignment with each other. Said table forms a portion of a loaf conveyor, which includes pairs of pusher members 35, which are mounted on arms 36 extending from the sleeves 37 that are fixed on the transverse shafts 38 to rotate therewith. Said shafts 38 are mounted for rotation in suitable bearings in the ears 39 provided on certain of the links of the sprocket chains 40, which sprocket chains travel over guide bars 41 that extend longitudinally of the machine at the sides of the table members 33 and 34 in upwardly spaced relation thereto. Also extending between the chains 40 in spaced relation to the shafts 38 are cross bars 42 and springs 43 having end portions 44 that hook around the cross bars 42 and coiled portions 45 extending around the shafts 38 and fixed at their coiled extremities to said shafts 38, said springs 43 operating to hold the rollers 46 in engagement with a guide bar 47, said rollers 46 being provided on the outer end of levers 48 that are keyed to the shafts 38.

The guide bar 47 is provided with a tapered end portion 49 and an upwardly curved portion 50, a downwardly curved portion 51 and a straight portion 52, as will be obvious from FIG. 7, said straight portion 52 extending lengthwise of the machine to the end of the table portion 34 remote from the table portion 33, and, as shown in FIG. 11, terminates in an upwardly curved portion 53 at the opposite end thereof from the end of the guide bar 47 shown in FIG. 7. The sprocket chains 40 are driven in the direction indicated by the arrows in FIGS. 7, 8 and 11 by means of a suitable driving means, not shown. The sprocket chains 40 operate over sprocket wheels at opposite ends of the same. One of said sprocket wheels 61 is shown in FIG. 7, said sprocket wheel being mounted for rotation on the transverse shaft 62.

As the rollers 46 on the levers 48 engage the guide bar 47 at the upwardly curved end portion 53 thereof, the arms 36 and pusher members 35 will move from the dotted line position thereof shown in FIG. 11 into the upper dotted line position thereof shown in FIG. 7 traveling along relative to the upper runs of the sprocket chains 40, in the position shown in the upper portion of FIG. 7 until the end 49 of the guide bar 47 is engaged by the roller 46 on the lever 48 associated with a pair of said pusher members 35 and arms 36. Upon engagement with the upwardly curved portion 50 of the guide bar 47 the arms 36 will gradually swing counter-clockwise, as viewed in FIG. 7, so that by the time the lower end of the downwardly curved portion 51 of the guide member is reached by the roller 46 the arms 36 will be swung to a position such that these arms will extend vertically downwardly and will continue in the lower dotted line position thereof shown in FIG. 7 along the entire straight portion 52 of the guide bar 47 until the upwardly curved portion 53 is reached.

The loaves that are to be wrapped, which are ordinarily sliced, are ordinarily fed from the slicing machine along a transverse track 63 by suitable conveying means which are common to machines of this character, and are not shown in the drawings. The loaf, indicated at 64 in FIG. 7, will have a somewhat inclined position on the track 63, being guided along the track by the upstanding flange 65 with which the loaf 64 engages. The usual wrapping

mechanism provided in commercial bread wrapping machines, has a continuous length 66 of wrapping material of desired width fed to the same from a roll of said material and said continuous length or web of wrapping material passes over a guide roller 67, which is located in approximately the position shown in FIG. 7 with respect to the loaf 64 when it reaches its final position for the commencement of the wrapping operation, with an end portion 68 of said wrapping material extending down over the loaf and below the top edge of the track 63 as shown in FIG. 7. Said commercial wrapping machines are ordinarily provided with a pusher member 69, the operation of which is timed so that, after the loaf has reached the position shown in FIG. 1, said pusher member moves to the left sufficiently to push the loaf and the wrapping material engaged therewith onto a movable support 70, which support is in the full line position shown in FIG. 7 at the time that this action takes place. Said supporting member 70 is in the form of a plate which has a reduced end portion 71 shown in FIG. 1, that is mounted to pivot about the axis of the shaft 72 mounted on the frame members 31. Arms 73 and 74 are mounted on the brackets 75, which brackets are also mounted to swing about the shaft 72 as an axis, along with the supporting member 70. Said brackets are provided with sleeves 76 that are mounted on the shaft 72 to turn thereon, and are further provided with bearing members 77 in which the pivot pins 78 are mounted, and with rollers 79 that operate between the flanges 80 of a channeled guide bar mounted for limited movement transversely of the length thereof on the supporting member 70.

Mounted for rotation in suitable bearing members 81 on the frame members 31 is a shaft 82, which has oppositely threaded portions 83 thereon that have correspondingly screw-threaded sleeves 84 mounted thereon for adjustment toward and away from each other by rotation of the shaft 82. A cam portion 85 is provided on each of said sleeves 84, which cam portions engage with the bracket members 75. The cams 85 are provided with high portions that are engaged by the members 75 when the loaf supporting member 70 is in its down position, which is the full line position thereof shown in FIGS. 5 and 7, such engagement causing a movement of the channeled guide member that has the side flanges 80, toward the left in FIG. 1, and causing the brackets 75 to swing about the pivots 78 so that the arms 73 and 74 will have the dotted line position thereof shown in FIG. 1. The arms are urged toward the full line position shown in FIG. 1 and the brackets 75 are urged toward the cams 85 by any suitable means, such as a coil spring, extending between the pivot pins about which the rollers 79 rotate, such a spring being shown at 86 in FIG. 1.

The conveyor 63 deposits the loaf 64 in such a position that it will be in transverse alignment with the space between arms 73 and 74 when it reaches its delivery position on the conveyor 63. Accordingly, when the pusher member 69 moves the loaf 64 to the left in FIG. 7 onto the supporting member 70 in its lowered position, the arms 73 and 74 will be in their separated or dotted line position, as shown in FIG. 1, and the loaf will readily move into position between the arms 73 and 74 into the position shown in FIG. 19. At the time that this movement takes place, the depending end 68 of the wrapping material will be drawn in under the loaf between the plate 70 and the loaf 64, into the position relative to the loaf shown at 87 in FIG. 19. As the loaf with the wrapper partly around it moves onto the supporting member 70 the wrapper will be engaged by the arms 73 and 74. The arm 74, which may be referred to as a tucker, acts as a folding member to fold a portion of the wrapper projecting from one end of the loaf, as shown at 88 in FIG. 19. The portion 87 of the wrapper that is under the loaf is also folded over as shown at 89 by the arm 74, which, as will be obvious from FIG. 19, has a rectangular portion 90 that engages the wrapper.

It is not desired to fold the other end of the wrapper that engages the arm 73, and the arm 73 is accordingly cut away as shown at 91 to provide a reduced end portion 92 thereon, which acts as holding or guide means for the end of the sliced loaf 64 that is adjacent the arm 73. The arm 73 is also narrower than the arm 74 and has a downwardly inclined edge portion 93 that provides a downwardly projecting enlargement 94 between the cut-away portion 91 and the downwardly inclined portion 93. The action of the portions 91 and 92 of the arm 73, in movement of the loaf 64 onto the supporting member 70 and into engagement with said arm 73, will cause the projecting end 95 of the wrapping material to be pushed downwardly below the top of the loaf at the upper side of the projecting portion of the wrapper and the wrapping material 95 will be pushed somewhat inwardly toward the free edge of the portion 87 that is located under the loaf, as shown in FIG. 19. The arm 73 thus acts as a guide to support and position the adjacent end of the loaf to maintain the proper positioning thereof while permitting the wrapper to extend outwardly therefrom as illustrated in FIGURE 22.

Upon the loaf reaching a position in which it is confined completely between the arms 73 and 74 and entirely supported by the supporting plate 70 and the pusher member 69 moves away therefrom and the supporting member 70 is swung upwardly about the axis of the shaft 72 by suitable operating means, which is ordinarily provided on the wrapping machine, moving to the dotted line position thereof shown in FIGS. 5 and 6. The arms 73 and 74 are moved inwardly toward each other into the full line position as this movement of the supporting member 70 takes place. A stationary folding plate 96 is mounted on a support 97 extending from the frame member 31. As the supporting member 70 moves from the full line to the dotted line position thereof, or from its depressed to its elevated position, as shown in FIG. 5, with the rectangular folding portion 90 thereof between the folding plate 96 and the end of the loaf, the end of the wrapper which extends outwardly from the end of the loaf adjacent the member 74 is engaged by the folding member 96 to fold the upper portion of the wrapper downwardly, as shown at 98 in FIG. 21, said folding plate 96 having a downwardly inclined edge portion 99 and an upwardly inclined edge portion 100 extending to the extremity thereof, to thus provide a rounded downward projection 101 thereon, said inclined portion 100 and rounded portion 101 serving to fold the projecting end of the wrapper into the downwardly extending fold 98. During the upward movement of the supporting member 70 to the dotted line position thereof shown in FIGS. 5 and 7, the wrapping material 66 is engaged with a cutter (not shown), which is so positioned that it cuts off the desired length of the wrapper for extension completely around the loaf and to provide an overlapped seam on the under side of the loaf.

After the downward fold 98 has been made by the upward movement of the loaf along with the supporting member 70 into its dotted line position, one pair of the pusher members 35 reaches the position at which the roller 46 on the arm 48, associated with said pair of pusher members, engages the straight portion 52 of the guide bar 47 where the downwardly curved portion 51 joins said straight portion 62, and said pusher members 35 will engage the loaf 64 to move it from the supporting member 70, to the right in FIG. 7, or to the left in FIG. 5. In such movement the loaf will first pass over a roller 102, which is mounted for free rotation about its axis on the frame and then onto the table portion 33, which has a depending flange 103 adjacent the roller 102. This movement draws the wrapper tightly around the loaf so as to closely conform to the cross sectional contour thereof.

The end of the wrapper, that was engaged by the arm 74 and by the folding member 96, moves into engagement

with a vertically extending guide plate 104, which has a suitable electrical heating element 105 and a curved guide flange 106 provided on the outer face thereof. Said guide plate has a curved edge portion 107, a straight bottom edge 108 and an upwardly inclined rear edge 109. A guide plate 110 is mounted in longitudinal alignment with the guide plate 104 and has a suitable electrical heating element 111 mounted on the outer face thereof and has an upwardly inclined forward edge 112 and an inclined guide flange 112' extending along said edge 112, as well as a straight bottom edge 113 engaging with the top of the table 33. The edge 108 of the guide plate 104, being spaced from the top of the table member 33, provides a horizontal slot 114 between the same and the top of the table 33, while the spaced inclined edges 112 and 109 provide an upwardly inclined slot 115 between the same.

The end of the length of wrapping material that has been cut off from the main body of wrapping material 66 hangs down on the side of the loaf 64 that is forward as the loaf is pushed onto the table portion 33, this depending portion of the wrapper being shown at 116 in FIG. 21. The extremity thereof will be dragged under the loaf on the under side of the end portion 87 of the wrapper, as shown at 117 in FIG. 21, as the loaf moves onto the table portion 33. A portion of the wrapper will thus be projecting outwardly from the loaf and will gradually be folded into the position thereof shown in FIG. 23 at 118, the portions 89 and 118 projecting from the loaf, as will be obvious from FIG. 23. These portions will be adjacent the top of the table 33 and will pass into the slot 114 between the guide plate 104 and the table top and eventually into the slot 115 as the loaf is moved along by the pusher members 35. Such movement of the projecting portions 89 and 118 in the slot 115 will cause the portions 89 and 118 to be folded upwardly to create the upward fold 119 of the wrapper. These folding operations are the same as are ordinarily carried out on both ends of a loaf in a wrapping machine and the sealing elements 105 and 111 act in the usual manner as the wrapper passes along adjacent the same to cause the wrapping material to be heated to the point that the material of the wrapper or the coating thereon will become tacky and will cause the plies to be sealed together after leaving the heating elements and cooling below the temperature at which the plies or the coating thereon will be in a tacky condition. The bottom portions 87 and 117 provide the overlapped seam at the bottom of the loaf and heating elements 120 and 121 on the under side of the table portion 33, are located as may be found desirable and provided in any number desired, to provide the desired heating and resulting sealing action of the overlapped seam on the under side of the loaf.

As the loaf 64 with the wrapper around it as shown in FIG. 19, moves away from the arms 73 and 74 over the roller 102 and onto the table portion 33, the other end of the wrapper, which is not to be sealed, has assumed the position shown in FIG. 20 with the projecting portion 95 thereof having a somewhat tubular shape and having been depressed somewhat on the upper side thereof by means of the arm 73 with the portions 87 and 117 on the lower side thereof in overlapped relation as shown in FIG. 20. While the guide plates 104 and 110 will confine the one end of the loaf so as to hold the slices in their proper side by side relationship as the loaf leaves the arm 74, means must also be provided for confining the other end of the loaf that has the portion 95 of the wrapper projecting therefrom. Said means comprises an upper guide bar 122, which is provided with an offset 123 therein to provide an outer end portion 124 thereon, which is upwardly and outwardly offset from the main body portion 122 of the guide bar and with which a guide plate 125 having an upwardly curved end portion 126 cooperates, said guide plate being mounted on a bracket 127 having a vertical shaft 128 provided thereon for mounting the plate 125 for adjustment

about the axis of said member 128, a suitable clamping member 129 being provided on the plate 125 for securing the plate in adjusted position on the bracket 127.

The shaft 128 is also vertically adjustable in the eye 5 130 provided on the end of the bracket 127, so that the plate 125 can be adjusted to the desired position to guide the wrapper into engagement with suitable guiding means, and the end of the loaf from which the wrapper portion 95 projects into engagement with the guide bar 122, as the loaf is moved from the supporting member 70 onto the table portion 33. The end portion 124 of the guide bar 122 and the guide plate 125 are located above the arm 73 when the loaf is on the supporting member 70 in its raised, dotted line position, as shown in 10 15 FIG. 7. Cooperating with the upper guide rod 122 is a lower guide rod 131, which has an inclined upper edge 132 providing a tapered end portion 133 thereon, which terminates closely adjacent the top surface of the table portion 33 at the end thereof adjacent the roller 102 and 20 serves to guide the lower portions 117 and 87 of the projecting wrapper portion 95 upwardly from the level of the top of the table 33.

The guide bars 122 and 131 are mounted on a plurality of horizontally extending bracket arms 134 and 25 135, that are mounted on vertically extending bracket members 136, which are mounted for vertical adjustment on the brackets 137 by means of the headed fastening element 138 on the bracket member 137 that extends through a slot 139 in the bracket member 136. 30 Mounted laterally outwardly from the guide bars 122 and 131 on the horizontal bracket members 134 and 135 so as to be in substantial horizontal alignment, respectively, with the under side of the guide bar 122 and the top side of the guide bar 131, are the guide members 140 35 and 141, the guide members 140 being in transverse alignment with each other, and the guide members 141 being in transverse alignment with each other. The guide members 140 and 141 are made of small rods or wires. Said guide members 140 will thus extend in parallelism 40 to the guide member 122 and in horizontal alignment therewith and the guide members 141 will extend in parallelism to the guide member 131 and in horizontal alignment therewith, said guide members 140 and 141 being located laterally outwardly from the guide members 122 and 131, respectively. Transverse bracing members 142 are also provided between the guide members 45 140 and 141 between the bracket arms 134 and 135.

It will be obvious that the guide members 122 and 131 along with the guide members 140 and 141 can be 50 adjusted so as to vary the vertical position thereof with respect to the top of the table portion 33. Said guide members are mounted on the bracket members 136 and 137 so that the guide member 122 inclines downwardly from the end thereof having the guide plate 125 associated therewith and the guide member 131 inclines upwardly from the end 133 thereof, said guide members 122 and 131 and the guide members 140 and 141 thus gradually approaching each other in a direction away from the ends thereof at which the wrapper portion 60 95 first engages therewith.

The loaf, as it is moved along the table portion 33 by means of the pusher members 35, to the end thereof adjacent the table portion 34, is confined between the guide bars 122 and 131 at one end and the guide plate 65 110 at the other end thereof. Thus, while one end of the wrapper is being folded and sealed, and the under side of the wrapper sealed air tight, at the overlapped joint made up of the end portions 87 and 117 of the wrapper, by engagement with the various folding and heating means and the cooling thereof after disengagement from said heating means, the other end 95 of the wrapper is being gradually gathered together in a flattened somewhat oval form, as shown in FIG. 13. The portion 95 of the wrapper extends outwardly from the 70 75 loaf 64, as shown in FIG. 14, the guide bar 122 forcing

the wrapper downwardly around the end of the loaf 64, as shown at 143, and the guide bar 131 forcing the wrapper upwardly around the end of the loaf, as shown at 144, so that the wrapper closely follows the contour of the end of the loaf except for the projecting portion 95 between the two guide bars 122 and 131.

Extending from the ends of the guide bars 122 and 131, remote from their entrance ends, are guide plates 145 and 146. Said guide plates are in longitudinal alignment with said guide bars. Mounted in transverse alignment with the bottom edge of the guide plate 145 and the top edge of guide plate 146, in a similar manner to the alignment of the guide members 140 and 141 with the guide bars 122 and 131, are the guide rods 147 and 148, the guide rods 147 having the upwardly curving end portions 149 and 150 at opposite ends thereof and the guide rods 148 having downwardly curving end portions at opposite ends thereof, the downwardly curved portion at one end thereof being shown in FIG. 3 at 151 and at the other end thereof at 152 in FIG. 26.

A longitudinal plate-like frame member 54 is provided in outwardly transversely spaced relation to the guide plates 145 and 146. Transverse braces 55 are provided for properly spacing the guide rods 147 and 148, said transverse braces 55 being fixed to said guide rods 147 and 148 and extending between the guide plates 145 and 146 and the longitudinal frame member 54. Said transverse bracing members 55 are secured rigidly in fixed position to said guide plates 145 and 146 and the frame member 54. Referring now to FIG. 26, it will be noted that the guide plates 145 and 146 have inclined edge portions 56 and 57 thereon and straight parallel edge portions 58 and 59 extending from the inclined entrance edges 56 and 57, thus providing a gradually narrowing slot 60 between said guide plate 145 and 146 at the entrance end thereof leading to the narrow slot defined by the edges 58 and 59 thereof. The end of the guide rod 122 extends under the downwardly inclined edge 56 of the guide plate 145 and the guide rod 131 extends slightly beyond the guide rod 122 and over the upwardly inclined edge 57 of the guide plate 146. The guide rods or wires 147 and 148 extend substantially parallel to the bottom and top edges, respectively, of the guide plates 145 and 146, except that the lower guide members 148 have portions 184 that overlap the end portion of the guide rod 131 and align therewith, said guide member 131 having a tapered extremity 185. The extending portion 95 of the wrapper will thus be guided into the tapering slot 60 and into the narrow passage therefor provided between the parallel edges 58 and 59 of the guide plates 145 and 146.

Cooperating with the guide rods 147 and 148 are grooved friction rollers of yieldable material 153 and 154, the rollers 153 receiving the rods or wires 147 in the grooves 155 thereof and the rollers 154 receiving the rods or wires 148 in the grooves 156 thereof. Said rollers are rotated in the directions indicated by the arrows in FIG. 3. Also cooperating with the guide rods 147 and 148 are grooved metal rollers 157 and 158, which are provided with the grooves 159 and 160 receiving the wires or rods 147 and 148, respectively, and rotating in the directions indicated by the arrows in FIG. 3. The purpose of the rollers 153 and 154, which are of resilient gripping material, such as rubber, is to align the extended portions 95 of the wrappers with the end centers of loaves 64 so that the same will be centered relative to the longitudinal axis of the loaf. Due to the fact that the loaf is being positively moved forwardly along the table portions 33 and 34 by the pusher members 35, and because of the frictional engagement of the wrapper portion 95 with the guide members 122, 131, 140, 141, 145, 146, 147 and 148, the extended portion 95 of the wrapper will lag behind the loaf 64. It is desirable that this lagging of the wrapper be corrected

so that when the wrapper is twisted the twist will be substantially centrally of the loaf at the end thereof at which the extended portion 95 of the wrapper is located. In order that this straightening is accomplished, the rollers 153 and 154 are rotated at a higher peripheral speed than the speed of forward movement of the loaf on the table portion 34. It will also be noted that the peripheries of the rollers 153 and 154 project toward each other beyond the guide rods 147 and 148 to thus positively grip the extended portion 95 of the wrapper between them.

Mounted on the frame 30 is a motor 161 (see FIGS. 2 and 8), which is provided with a sprocket wheel fast on the shaft 162 thereof that drives the sprocket chain 163 in the direction indicated by the arrows in FIG. 8. The sprocket chain 163 operates over a sprocket 186 fixed on the shaft 164, which also has a gear 165 mounted thereon to rotate therewith, that meshes with the gear 166 that is fixed on the shaft 167. Thus the shafts 164 and 167 rotate, in the direction indicated by the arrows in FIG. 8, at the same speed. The shafts 167 and 164 have the rollers 153 and 154 mounted thereon to rotate therewith. The size of the sprockets and the rate of rotation of the shaft 162 is such that the shafts 164 and 167 rotate at such a speed that the peripheral speed of the rollers 153 and 154 will be considerably greater than the rate of travel of the sprocket chain 40, which carries the pusher members 35 lengthwise of the table portions 33 and 34.

30 A sprocket 168, which meshes with the lower run of the sprocket chain 40, is mounted on the shaft 169 to rotate therewith, and a sprocket 170 is also mounted on the shaft 169 to rotate therewith, the sprocket chain 171 extending over the sprocket 170 and being driven in the direction of the arrows in FIG. 8. The sprocket chain 171 operates over a sprocket 187 that is fixed on the shaft 172, on which the gear 173 is also mounted to rotate therewith, the gear 173 meshing with a gear 174 on a stub shaft 175. The shafts 172 and 174 have the rollers 157 and 158 mounted thereon to rotate therewith. The sprocket drive means for the shaft 172 is of such a character that the peripheral speed of the rollers 157 and 158 at their peripheries 176 and 177 is approximately that of the speed of the sprocket chains 40. It will be noted, upon reference to FIG. 3, that the peripheral portions 176 and 177 of said rollers are quite close together, where the guide rods 147 and 148 pass through the grooves 159 and 160 of said rollers, projecting considerably inwardly toward each other beyond said guide rods 147 and 148, thus pressing the projecting portion of the wrapper 95 into a quite flattened shape, this flattened condition of the projecting portion 95 of the wrapper being shown clearly in FIGS. 15 and 16.

55 A pair of upstanding brackets 178 is provided on the frame 30, said brackets each having a screw-threaded opening therein closely receiving the screw-threaded portion 179 of a mounting member 180, which is mounted for rotation but against endwise movement in the guide plate 181. Said guide plate has an outwardly curved 60 entrance end 182 and is adjusted by means of the hand wheel 183 toward and away from the guide plates 145 and 146, the guide plate 181 being preferably adjusted to a position such that the end of the loaf that has the projecting end of the wrapper portion 95 will be kept in close engagement with the guide plates 145 and 146. The plates 104, 110 and 181 (in conjunction with tucker 74 and folding plate 96) thus cooperate to form abutment means extending lengthwise of the loaf conveyor, which abutment means includes the means to fold and seal one end of the package and also positions that folded and sealed end. Said abutment means cooperates with the guiding surfaces on arm 73, the bars 122 and 133, and plates 145 and 146 that face said abutment means to confine the loaf between said guiding surfaces and abutment means.

Mounted on the shafts 172 and 175 are sprocket wheels 188 and 189, with which the sprocket chains 190 and 191 engage (see FIG. 27). Mounted on the guide plates 145 and 146 on pivot members 192 and 193 are the bell crank levers 194 and 195. A spring connects the one arm of each bell crank lever with the guide plate upon which it is pivotally mounted to urge the bell crank lever 194 about the pivot 192 in a counter-clockwise direction and the bell crank lever 195 about the pivot 193 in a clockwise direction, the spring attached to the bell crank lever 194 being indicated by the numeral 196 and the spring attached to the bell crank lever 195 by the numeral 197. Mounted on the other arms of the bell crank levers are stub shafts 198 and 199 on which the sprockets 200 and 201 are mounted, the sprocket chain 109 extending around the sprocket 200 and the sprocket chain 191 extending around the sprocket 201. The action of the springs 196 and 197 is to urge the sprockets 200 and 201 toward each other, and thus the sprocket chains 190 and 191 toward each other into close gripping engagement and with the extending end 95 of the wrapper. Said sprocket chains 190 and 191 will be traveling at substantially the peripheral speed of the rollers 157 and 158 and will thus engage with the extending end 95 of the wrapper to carry it along at the same rate as the bread loaf 64 after the extended end portion 95 of the wrapper has been aligned with the longitudinal center of the loaf by means of the rollers 153 and 154, and this action of the chains 190 and 191 will continue until the peripheries of the rollers 157 and 158 engage with the extending portion of the wrapper 95 to carry it toward the left in FIG. 3 to the twisting mechanism.

Referring to FIG. 4, a hollow shaft 202 is mounted in a bearing 203 provided on the frame member 54 and is provided with a gear 204 mounted to rotate therewith, which meshes with a gear 205 mounted on a shaft 206, said shaft being mounted in a bearing 207 on the frame member 54. Said shaft 206 is driven at intervals through mechanism to be described below. The hollow shaft 202 has the twisting member 208 mounted thereon to rotate therewith, said twisting member 208 being provided with a hollow boss 209, in which the end of the shaft 202 is secured in liquid tight relation against relative rotation and against endwise movement. The bearing member 203 is a thrust bearing and is of such a character that the end face 210 of the boss 209 will be slightly spaced from the frame member 54.

The twisting member 208 is of a substantially U-shaped character having a pair of hollow arms 211 and 212 and a hollow connecting portion 213, the arms 211 and 212 terminating in end portions 214 and 215. The cross sectional shape of the end portions 214 and 215 is shown in FIGS. 16 and 18, said portions extending toward each other and terminating in flanges 216 and 217 that extend longitudinally of the twisting member forming portions of the clamping jaws of said twisting member extending longitudinally of the machine. Co-operating with the flanges 216 and 217 are plates 218 and 219 that are secured to the flanges 216 and 217, respectively, by suitable securing elements to clamp the marginal portions 220 and 221 of flexible members 222 and 223 fluid tight between the flanges 216 and the plate 218 and between the flanges 217 and the plate 219. The plates 218 and 219 have central openings 224 and 225 therein to provide communication between the passages 226 and 227, in the hollow body portion of the twisting member 208, and the interior of the flexible members 222 and 223.

A fluid tight swivel coupling 228 connects the hollow shaft 202 with a flexible compressed air conduit 229, to which air under pressure is supplied by a suitable valve, which is provided with controlling means for supplying the air under pressure at proper intervals thereto so that the flexible members 222 and 223 will be inflated into

the position shown in FIGS. 17 and 18 from the position shown in FIGS. 15 and 16. The opening 230 existing between the inflatable members 222 and 223, comprising the gripping jaws of the twisting member, is in alignment 5 with the opening between the guide members 147 and 148 at the discharge end thereof, when the twisting member is in wrapper receiving position, so that the extending end 95 of the wrapping material can readily pass between said jaws as will be obvious from FIGS. 15 and 16. The loaf 64 will be in close contact with the guide plates 10 145 and 146 with the extended portion of the wrapper 95 extending through the slot between the bottom edge 58 of the guide plate 145 and the top edge 59 of the guide plate 146 at this time. Upon inflation of the 15 gripping members 222 and 223 the extended portion 95 of the wrapper will be squeezed together, as indicated at 95', between the then closed gripping jaws 222 and 223 to firmly hold the extended wrapping material 95 between said jaws.

The shaft 167 has a sprocket 231 mounted thereon to rotate therewith, over which the sprocket chain 323 operates, which also operates over a sprocket 233 provided on a clutch mechanism 234, which is of such a character that it rotates the shaft 207 one complete revolution for 20 each time that the clutch 234 is thrown into driving position. Suitable controlling means for the clutch is provided so that it will be actuated to drive the shaft 206 at such a time that the extending end portion 95 of a wrapper of a bread loaf 64 will be in position between the gripping jaws 222 and 223 and said jaws will have been inflated to grip the extended end 95 of the wrapping material. In order that the clutch mechanism and the shaft 206 will be halted at such a position that the gripping jaws 222 and 223 will be in a position with 30 the opening 230 between the same in alignment with the opening between the guide members 147 and 148, locking fingers 235 and 236 are provided that have hub portions 237 and 238 that are freely rotatably mounted on a stub shaft 239 extending from the frame member 54.

The finger 235 cooperates with the cam member 240 mounted on the shaft 206 in fixed position. The shaft 206 is connected with the output side of clutch 234, said clutch being of such a character that when the shaft 206 is held against rotation the clutch will disengage. 40 The holding finger 235 has a nose portion 242 thereon, providing a right angular stop shoulder 243 (see FIG. 10). The cam 240 has a high portion 244 that terminates in a right angular shoulder 245, with which the shoulder 243 engages to limit rotation of the shaft 206 in a clockwise direction as viewed in FIG. 10.

A disk 241 is mounted on shaft 246 to rotate therewith (see FIG. 32). Said disk has a slot 338 therein, which is engaged by a depending locking portion 339 on the locking finger 236, that fits the slot 338 closely. The 50 disk 241 is adjustable relative to the gear 205 by means of headed fastening element 350 screw-threadedly engaging in an opening in the gear 205 and engaging in an arcuate slot 341 in the disk 241. By providing the pin and slot connection between the stop disk 241 and the gear 205, it will be seen that the gear and disk can be adjusted circumferentially of the shaft 206 relatively so that the engagement of the locking portion 339 with the slot 338 will exactly line up the jaws of the twisting member 208 with the guide members 147 and 148, as shown in FIG. 65 16.

Means is provided for lifting the holding fingers 235 and 236 to permit rotation of the shaft 206 and the gear 205 comprising a plunger 246, which is actuated by a piston in the compressed air cylinder 247 to project the plunger 246 upwardly against the under side of the finger 235 to lift the same up sufficiently to disengage the shoulder 243 on the finger 235 from the shoulder 245 on the cam. The hub 238 of the finger 235 has a lateral projection 336 thereon engaging a shoulder 337 on the hub 237 to lift the finger 236 along with the finger 235 to disengage 70 75

the locking portion 339 from the slot 338. Compressed air is supplied to the cylinder 247 through the conduit 342 by operation of a solenoid valve to be described below, so as to project the plunger 246 against finger 235 to lift it and immediately return to retracted position. When disengagement of the locking portion 339 from the slot 338 takes place, the shaft 206 will rotate one revolution, since the locking fingers 235 and 236 will have the locking portions thereof in position to again engage with the shoulder 245 and slot 338 during rotation of the cam 240 and disk 241 with shaft 206 after only a small arcuate movement of the same out of locking position. The size and relative movement of teeth on the gears 204 and 205 is such that the hollow shaft 202 will rotate a plurality of turns for each turn of the shaft 206, thus rotating the twisting member the same number of times about the axis of said shaft. The relative sizes of said gears is chosen in accordance with the number of twists it is desired to give the end 95 of the wrapper.

When the loaf 64 reaches the dotted line position thereof shown in FIG. 11, the pusher members 35 will leave said loaf, due to the movement of the arms 36 in an upward direction, because of the engagement of the roller 46 with the upwardly directed guide bar portion 53. At this time the loaf 64 will be deposited on the table 248 and will be moved into engagement with a switch actuating member 249 of a switch 250, which is mounted on the guide plate 181, and the closing of which switch 250, by engagement of the loaf with the switching element 249 to move it out of normal position, initiates operation of the controlling means for carrying out the various operations of the twisting and tying mechanism in sequence. The loaf 64, which in the position shown in FIG. 11, is located with respect to the twisting mechanism in such a position that the longitudinal middle of the loaf will be substantially on the axis of rotation of the twisting member 208 and of the hollow shaft 202. Rotation of the hollow shaft, after the gripping jaws 222 and 223 have moved to the position shown in FIGS. 17 and 18, will twist that part of the extending portion 95 of the wrapper that is located between the end of the loaf 64 and the gripping jaws 222 and 223 the number of times that the shaft 202 turns about its axis. When this twisting movement of the twisting member has taken place, the twisted portion 251 of the wrapper will extend from the slot provided between the guide plates 145 and 146 to the gripping jaws 222 and 223, as shown in dotted lines in FIG. 17.

Mounted on a frame member 252 is a bracket 253, on which is mounted a compressed air cylinder 254, to which air under pressure is supplied at one end thereof through the pipe 255 and adjacent the other end thereof by pipe 343. A piston operates in the cylinder 254 and the piston rod 256 extends from the cylinder and is connected with the body portion of a vertically movable slide 257 so as to move therewith. Pivot pins 258 project from opposite sides of the slide 257 and have rollers 259 mounted thereon for rotation, said rollers having beveled faces 260. Said rollers 259 engage with vertical guide members 261 that are mounted on the guide plate 146.

The slide 257 is provided with a pair of spaced supporting surfaces 262 for a tie member 263, there being side flanges 264 on said slide 257 on opposite sides of the supporting surfaces 262, to thus provide a groove in the slide 257 in the bottom of which the tie member 263 is located. Said side flanges have reduced portions 265 connected with the taller portions of said side flanges by means of curved edged flanges 266. A recess 267 having a curved bottom wall 268 is provided between the two tie supporting surfaces 262. The tie member 263 extends across the recess 267, being thus supported at spaced points by the supporting portions 262. (See FIG. 29.)

Means is provided for feeding the tie member 263 into position on the slide 257 and cutting the same off so that a length thereof extends longitudinally of the machine

across the slide 257. The tie material comes in the form of a continuous length of, preferably, flat material comprising parallel ductile wires and a suitable flat covering of a plastic material, and is mounted on a reel 269, which is mounted on a pivot member 270 provided on a depending bracket 271 on the guide plate 146. The continuous length of tie material 263 extends over a tensioning roller 272, which is mounted for rotation on a pivoted arm 273, and mounted on a pivot 274 on the guide plate 146, and which is provided with a tension coil spring 275, extending between the same and a bracket 276 on the guide plate 146. Then said tie material 263 extends over a flanged guide roller 277 mounted on a pivot 278 provided on the guide plate 146. From the flanged guide roller 277 the tie material passes through a tubular guide 279 to a pair of feed rollers. The feed rollers are provided with knurled drums 344 engaging the tie material 263 (see FIG. 31), and are driven in a feed direction by ratchet drive means interposed between the drums and gears for driving said ratchet mechanisms. The gear 280 for the lower feed roller is mounted on the shaft 282 to rotate therewith and the gear 281 for the upper feed roller is mounted for rotation on the stub shaft 283 on arm 284 pivoted on guide plate 146 at 285. The teeth 286 on said gears mesh to drive the feed rollers associated therewith in opposite directions.

The shaft 282 extends through a suitable bearing provided on the frame member 287 that is provided with end portions 288 and 289 that are secured, respectively, to the guide plate 146 and the frame member 54 (see FIG. 2). A gear 290 is mounted on the shaft 282 to rotate therewith and meshes with a rack 291 that is provided with teeth 292. A suitable guide member 293 is mounted on the frame member 287, being provided with flanges 294, between which the rack 291 is guided. Means for reciprocating the rack 291 is provided, comprising a compressed air cylinder 295, which is provided with a piston and a piston rod connected with said piston, which is connected with the rack 291 to move therewith.

Air, under pressure is selectively supplied to the cylinder 295 through the compressed air conduits 297 and 345.

The stroke of the piston in the cylinder 295 is of such length that the rack will rotate the gears 280 and 281 exactly the right amount to feed the desired length of the tie material 263 at each reciprocation of the rack 291, for the length of material to lie between the two guide members 261 with the end thereof in engagement with the right hand guide member 261 shown in FIG. 3. Said tie material 263 passes through a guide member 298 after passing between the two feed rollers and then through a suitable opening 299 in the left hand guide member 261, below hardened steel shear blade 346, which opening is in alignment with the bottom wall of the groove in the slide 257 (see FIGS. 29 and 30). A hardened steel shear blade 300 is mounted on the slide 257 and cooperating shear blade 346 is mounted in a recess 347 in guide member 261 and is urged toward the slide 257 by a spring 348.

As the slide 257 moves upwardly from the position shown in FIG. 29 to the position shown in FIG. 30, the shear blade 300 on the slide 257 will pass shear blade 346 to shear off the tie member to the proper length. Timed operation of the parts is such that the slide 257 will be in its down position shown in full lines in FIGS. 3 and 29 when the feeding operation of the tie material occurs. Upon upward movement of the slide 257 to the position shown in FIG. 30, the tie member 263 will be carried upwardly on the spaced supporting ledges 262 until the twisted portion 251 of the wrapper is engaged by the tie member in its upward movement, further upward movement causing the twisted wrapper portion to bend upwardly as shown in FIG. 33, and the tie member 263 to bend therearound, such movement being assisted by the curved bottom wall 268 of the recess 267, which serves as a forming die to bend the tie member into a

U-form, as shown in FIG. 30, with the two upstanding legs 301 thereof extending upwardly from the bend 302 therein, in substantially parallel relation and with the two legs 301 of substantially the same length. During this upward movement of the slide 257 the extending wrapper portion 95 remains clamped between the clamping jaws 222 and 223.

Mounted on the guide plate 145 is a bracket 303, which has a bearing 304 mounted thereon for a shaft 305. Said bracket is provided with a depending L-shaped bracket 306, which is engaged by a rack 307, which has teeth thereon that mesh with the teeth on the pinion 308 mounted on the shaft 305 to rotate therewith. The rack 307 has a guide block 309 fixed thereto slidably engaging the guide plate 145 and is connected with a piston rod 310 to move therewith, said piston rod 310 extending from a piston in the compressed air cylinder 311. The cylinder 311 is mounted on a bracket 312 on the guide plate 145, and has compressed air conduits 313 and 314 connected with the interior thereof. The piston in the cylinder 311 is reciprocated in the cylinder by alternately supplying air under pressure thereto through the conduits 313 and 314.

Mounted on the bottom end of the shaft 305 is a tie twisting mechanism comprising the fingers 315 at the end of shaft 305, having transverse portions 459 and portions 460 extending upwardly and outwardly at an oblique angle from the transverse portions 459, as will be obvious from FIGS. 3, 4 and 37, on diametrically opposite sides of the shaft 305. When the tie member has been moved to the position shown in FIG. 30 with the upstanding legs 301 thereof extending from the U-shaped portion 302, the ends of said upwardly extending legs 301 will be positioned between the two twisting fingers 315, as will be obvious from FIGS. 3, 4 and 37. Upon rotation of the shaft 305 the legs 301 of the tie member will be twisted together, said shaft turning the requisite number of times during a stroke of the piston in one direction within the cylinder 311 that the necessary number of twists provided in the tie member will be given thereto to tightly grip the twisted portion 251 of the wrapper closely adjacent the end of the loaf 64. Said twisted portion of the tie is indicated by the numeral 316 in FIG. 25. Upon completion of the one stroke of the piston in the cylinder 311 and completion of the tie twisting operation thereby, the slide 257 is returned to its position with the supporting surfaces 262 in alignment with the guide member 298, after which the return stroke of the piston in the cylinder 311 takes place and a feeding movement of the knurled tie feed rollers takes place to move another length of the tie material into position on the spaced supporting surfaces 262 of the slide 257.

The framework of the table 248 is provided with bearings for a pair of shafts 317 and 318, on which sprocket wheels 319 and 320 are mounted to rotate therewith. Also mounted on the shaft 318 to rotate therewith is a gear 321 (see FIGS. 11 and 12). Meshing with the gear 321 is a gear 322 mounted on the stub shaft 323 to rotate therewith, a sprocket wheel 324 also being mounted on the shaft 323 to rotate therewith, and having the sprocket chain 325 operating over the same. Said sprocket chain also operates over a sprocket wheel 326, which is mounted on the shaft 62 to rotate therewith, which is rotated by means of a sprocket 61 at the opposite end of the machine from that shown in FIG. 7, over which one of the sprocket chains 40 operates. The sprocket chain 325 is held under tension by means of a sprocket wheel 327, which is mounted on a pivot member 328 on the arm 329 pivotally mounted at 330 on the frame of the table 248.

The sprocket chain 40, traveling in the direction indicated by the arrow in FIG. 12, will rotate the sprocket wheel 61 in the direction of the arrow thereon and will drive the sprocket chain 325 in the direction indicated by

the arrow in FIG. 12, rotating the gears 322 and 321 in the directions indicated by the arrows thereon and thus the sprocket 320 in the direction indicated by the arrow thereon in FIG. 11. The sprocket chain 331 is driven in the direction indicated by the arrow in FIG. 11 by the sprocket 320. There is a sprocket 320 at each end of the shaft 318 and a sprocket chain 331 on each side of the table 248. Between said sprocket chains extend the transversely extending pusher bars 332, said pusher bars being offset slightly from the sprocket chains so as to be slightly spaced above the top of the table 248 as they pass along over the same. The table top is provided with obliquely extending flanges 333 for guiding the cross bars 332 onto and off the table top.

The timing of the mechanism is such that when the twisting operation of the tie member 263 has been completed one of the pusher bars 332 will engage the wrapped loaf 64 and will carry it away from the station at which the twisting of the wrapper and tying of the package has taken place, said pusher bar pushing the wrapped and tied loaf off the end 334 of the table 248. After the wrapped and tied loaf passes from the position in which the twisting and tying operations take place, the tied and twisted extending end of the wrapper is freed of the guide plates 145 and 146, the guide plate 145 having an upwardly offset bottom edge 349 and the guide plate 146 having a downwardly inclined top edge 335 so as to provide for free passage of the projecting end of the wrapper as the loaf is moved along the table 248.

Referring to FIGS. 1, 2 and 8, a sprocket 350 is also mounted on the shaft 169 to rotate therewith, driving the sprocket chain 351 in the direction of the arrow on FIG. 8. The sprocket chain 351 also operates over a sprocket 352, which is mounted in a housing 353, and is mounted on the shaft 354 in said housing to rotate with said shaft, said sprocket rotating in the direction indicated by the arrow thereon in FIG. 8. Mounted on said shaft to rotate therewith are cams, one of which is shown at 355 in FIG. 34. The housing 353 is mounted on a suitable frame member 356. The cam 355 is provided with a cam projection 357 and the other cams that are mounted on the shaft 354 to rotate therewith, said cams being arranged in axial side by side relation on the shaft 354 are provided with cam projections 358, 359, 360, 361, 362 and 363.

Also mounted on a suitable transverse angular frame member 364 in the housing 363 is a row of switches, one of said switches 365 being shown in FIG. 34. Said switch has an operating member 366, which is engaged by a projection 367 mounted on a spring arm 368, which has a roller 369 mounted on the end thereof. It will be obvious that as a cam projection, on the cam disk that is in alignment with a roller 369, engages therewith, the finger portion 367 will engage the switch operating member 366 to move the switch 365 out of normal position, said switch returning to normal position upon disengagement of the roller 369 from the particular cam projection in alignment therewith, the switches 365 being arranged side by side in a row that extends parallel to the axis of the shaft 354 so as to align the various switch operating members 368 with the cam projections on the series of disks provided on the shaft 354. It will be noted that the shaft 354, being driven by the sprocket chain 40 through the sprocket 168 and sprockets 350 and sprocket chain 351, will be driven constantly.

In order that the cam projection that controls the first of the sequence of operations of the wrapper twisting and tying mechanism will be the first cam to close a circuit that will perform the desired operation in the right relationship to the other operations controlled by the operating circuit, means is provided that makes the actuation of the switch operating members 368 by the cam projections on the cams on the shaft 354 ineffective

until the cams have reached the proper position for carrying out the succession of operations in the order in which it is desired to carry the same out.

In order to do this, and to assure that a loaf will be in position that the wrapper will be acted on by the wrapper twisting and tying means, a relay is provided that serves to throw the circuits controlling the succeeding operations into operative condition, which relay is controlled by the switching member 250 that is actuated by the loaf 64 when it reaches its desired position, and a switching member that carries out the first of the successive operations of the series of operations that have to be performed to accomplish the twisting of the wrapper and the tying of the same.

Referring to FIG. 36, circuit connections are shown, which include the line wires 370 and 371. A conductor 372 extends from the line wire 370 to one end of the winding of the relay 373, from the other end of which a conductor 374 extends to branch conductors 375 and 376. The conductor 375 leads to a solenoid valve 377, and the conductor 376 extends to the stationary contact member 378 of the switch 250 (see FIG. 1), which has the operating member 249 that is adapted to move the movable contact member 370 into engagement with a stationary contact 378. The conductor 380 extends from the movable contact member 379 to the stationary contact 381 of one of the switches mounted in the housing 353. The stationary contact 381 is provided on one of the switches 365, which has a movable contact 382, which is normally held open by means of a spring mounting member 383. The contact 379 is normally held in an open position by means of the spring mounting member 384.

When the cam projection 358 engages the roller 369 provided on the switch that has the movable contact 382, said movable contact is moved into engagement with the stationary contact 381 and the circuit is then completed from the conductor 370 through the conductor 372, winding of relay 373, conductors 374, 376, contacts 378, 379, conductor 380, contacts 381 and 382 and the conductors 385 and 386 to the line wire 371. The winding 373 of the relay will then be energized. When the relay 373 is energized the switching members 387 and 388 carried by the armature of said relay are moved so as to engage the stationary contacts 389 and 390. The engagement of the contact 387 with the contact 389 completes a holding circuit for the relay 373 through the conductor 391 and the normally closed switch having the movable contact 392 and the stationary contact 393, the circuit energizing the relay 373 then being from the conductor 370 through the conductor 372, winding of the relay 373, the conductor 394 leading to the movable contact 387, contacts 387 and 389, conductor 391, movable contact 392 and stationary contact 393 to the line conductor 371.

As soon as the cam projection 358 passes the roller 369 controlling the position of the switch 365 that has the movable contact 382, the contact 382 will again be moved to open circuit position. However, the contact 379 will remain in closed circuit position as long as the loaf is in position for the twisting and tying operations. The winding of the solenoid valve 377 remains energized because the circuit to the same remains closed, the circuit to said winding being from the line wire 370 to the conductor 395 and conductor 396 to one end of the winding of said solenoid and through the conductors 375, 374, 394, movable contact 387, stationary contact 389, conductor 391, movable contact 392, stationary contact 393 to the line conductor 371. Thus, as long as the relay 373 is energized the solenoid winding of the valve 377 will remain energized.

The solenoid valve 377 is of such a character that when the solenoid winding therein is energized the conduit 397 leading from a source of air under pressure is

connected with the conduit 229 leading to the twisting member 208, to supply air under pressure to the interior of the flexible members 222 and 223 inflating the same. The solenoid valve 377 is spring biased to return to normal position upon deenergization of its solenoid winding. In said normal position the valve 377 connects the conduit 229 with the outlet connection 398 leading to the outer air to deflate the flexible members 222 and 223.

Extending from the stationary contact 390 is a conductor 399 from which a conductor 400 extends, that is provided with branch conductors 401, 402, 403 and 404. Also a branch conductor 405 extends from the junction of conductors 399 and 400. The conductor 401 leads to a movable contact member 406, which is mounted on a suitable spring mounting member 407 that normally holds the movable contact 406 in open circuit condition with respect to the cooperating stationary contact 408, from which the conductor 409 extends. Said conductor 409 has the branch conductors 410 and 411 extending therefrom, the conductor 410 extending to a solenoid valve 412 and the conductor 411 extending to a solenoid valve 413. The solenoid valve 413 is of the same character as the solenoid 377 and connects the inlet pipe 414 extending from a source of air under pressure with the conduit 342 leading to the compressed air cylinder 247, which, upon being supplied with compressed air, actuates the plunger 246 to lift the fingers 235 and 236. When the solenoid in the valve 413 is de-energized, which takes place as soon as cam projection 359 has passed beyond roller 369, the conduit 342 is connected with an outlet connection 415 leading to the outer air, whereupon the plunger 246 will drop down into its lower position and be free of the fingers 235 and 236.

The winding of the solenoid valve 413 is included in a circuit from the line wire 370, through the winding, to the conductors 411, 409, contacts 408, 406, conductors 401, 400, 399, contacts 390 and 388 to the conductor 386 and back to the line wire 371, as long as the switch 40 having the movable element 406 remains closed. This is accomplished when the cam projection 359 (see FIG. 34) engages the roller 369 on the operating member for the switch having said contact member 406, and thus takes place immediately after the cam projection 358 has operated the switch controlled thereby to inflate the flexible clamping members 222 and 223.

At the same time that this action takes place, one of the windings in the double acting solenoid valve 412 is energized. The solenoid valve 412 is shown diagrammatically in FIG. 35 and is provided with an inlet connection 416 leading from a source of air under pressure and outlet connections 417 and 418, and with a valve chamber 419. Said valve chamber is provided with end walls 420 and 421, from which extend the passages 422 and 423 leading to the atmosphere. Solenoid windings 424 and 425 are mounted in said valve body 412 and the end portions of a plunger 426 are adapted to extend into said solenoid windings 424 and 425, said plunger serving as a movable core member for said solenoid windings. Mounted on said plunger to move therewith is a pair of valve members 427 and 428.

The plunger 426 is shown in the position which it assumes when the winding 424 is energized, in which position air under pressure will be supplied to the compressed air conduit 345 leading to the cylinder 295, and the conduit 297 will be open to the atmosphere through the valve 412, which will move the piston to the left as viewed in FIG. 9, causing the rack 292 to rotate the gear 290 in a clockwise direction to feed the tie material 263 into position on the slide 257. The winding 424 is energized when the movable contact member 406 engages the contact member 408, the circuit being from the line conductor 371 through the conductor 386, the contacts 388 and 390 and conductors 399 and 400, and branch conductor 401 to the contacts 406 and 408, and the conductors 409 and 410 to

one end of the winding 424. From the other end of winding 424 a conductor 429 extends to the conductor 430 leading out of the solenoid valve, which conductor is connected with the conductor 395 through a conductor 431 connected with the line wire 370. The solenoid valve 412 will remain in the position in FIG. 35 until the other winding 425 thereof is energized. The piston in the cylinder 295, having moved to the limit of its travel to the left, will remain in that position until it is returned to its original position upon energization of the winding 425, which will connect the compressed air conduit 416 with the conduit 297 and open the conduit 418 to the atmosphere.

When the cam projection 360 engages the roller 369 on the switch operating member associated therewith that has the movable contact member 432, which is normally held open by means of a spring mounting member 433, said contact 432 is moved into engagement with the stationary contact member 434. The movable contact member 432 is connected with the branch conductor 402 and the stationary contact member 434 is connected with a conductor 435, which extends to a winding in the solenoid valve 436, which is of the same character as the solenoid valve shown in FIG. 35. It will be noted upon reference to FIG. 35, that a conductor 437 leads from the other winding 425 thereof to the conductor 430. Thus the conductor 430 is connected with one end of each of the windings 424 and 425. The conductor 438 is similarly connected with both of the windings in the solenoid valve 436 and is in turn connected with a conductor 439, which is connected with the conductor 431 and thus with the line wire 370 through the conductor 395.

Accordingly, upon the contact 432 being moved into engagement with the contact 434 the left hand winding in the solenoid valve 436 will be energized, connecting the compressed air supply line 440 with the compressed air conduit 255 leading to the cylinder 254, which will cause the piston therein to move upwardly and the piston rod 256 and slide 257 to be moved upwardly to shear off a length of the tie member 263 and move it from the position shown in FIGS. 3 and 29 to the position shown in FIG. 30. Said slide 257 will remain in this position until the right hand winding in the solenoid valve 436 is energized.

The movable contact member 441, normally held in open position by means of the spring mounting member 442, is engaged with the stationary contact 443 when the cam projection 361 engages the roller 369 on the switch operating member that controls the position of the switch having said movable contact 441. A conductor 444 extends from the stationary contact 443 to one end of the left hand winding of a solenoid valve 445, the other end of said winding having the conductor 446 connected therewith in a similar manner to which the conductor 430 is connected with the left hand winding of the solenoid valve 412, and said conductor 446 is connected with the conductor 439.

Accordingly, upon closing of the circuit by engagement of the contact 441 with the contact 443 the left hand winding of the solenoid valve 445 will be energized, the circuit in which said winding is included being from the line wire 371 through the conductor 386, contacts 388 and 390, conductors 399, 400 and 403 to the movable contact 441 and from the stationary contact 443 through the conductor 444 and said winding to the conductor 446 and then through the conductors 439, 431 and 395 to the other line wire 370. When the left hand winding of solenoid valve 445 is energized the conduit 447 leading from a source of air under pressure is connected with the conduit 314 leading to the compressed air cylinder 311, moving the piston therein to the right to move the rack 307 to the right and rotate the shaft 305 of the tie twisting member counter-clockwise as viewed in FIG. 37 a plurality of times. As the piston in the cylinder 254 has been moved upwardly prior to this rotation of the twisting member, the tie member will be in the position

shown in FIG. 30 and the legs 301 thereof will be twisted about each other by the members 315 of the twisting member to tie the twisted end of the wrapper thereby.

The movable contact member 448, which is mounted on a spring mounting member 449, that normally holds the same out of engagement with the stationary contact 450, is moved into engagement with the stationary contact 450 when the cam projection 362 engages the roller 369 associated with the operating member for the switch having the movable contact member 450. A conductor 451 extends from the stationary contact 448 to the one end of the right hand winding of the solenoid valve 436. Upon closing of said circuit by engagement of the contact 448 with the contact 450 the right hand winding of solenoid valve 436 is energized, connecting the compressed air conduit 440 with the conduit 343, whereupon the piston in the cylinder 254 will be moved toward the left in FIG. 36, or downwardly as viewed in FIGS. 3 and 4, returning the slide 257 to its lowered position. The circuit that includes the right hand winding of the solenoid valve 436 is from the line wire 371 through the conductor 386, contacts 388 and 390, conductors 399, 400 and 404 to the movable contact 448, then to the stationary contact 450 and the conductor 451 to one end of the right hand winding in the valve 436 and from the other end of the winding through the conductors 438, 439, 431 and 395 to the other line wire 370. When the slide 257 returns to its down position, the upwardly bowed twisted portion 251 of the wrapper will return to a substantially horizontal position, freeing itself from the tie twisting member.

The movable contact member 452, which is mounted on a spring mounting member 453, which normally holds the same out of engagement with the stationary contact member 454, is moved into engagement with the stationary contact member 454 when the cam projection 363 moves into engagement with the roller 369 associated with the operating member for the switch having said movable contact 452. A conductor 455 extends from the stationary contact 454 and branch conductors 456 and 457 extend from the conductor 455. The conductor 456 extends to one end of the right hand winding of the solenoid valve 445. Upon closing of said circuit by engagement of the contact 452 with the contact 454 the right hand winding of the solenoid valve 445 is energized, whereupon the piston in the cylinder 311 is moved to the left and the tie twisting member having the arms 315 is rotated in a clockwise direction, the piston in said cylinder returning to a starting position for the next tie twisting operation. The circuit that includes the right hand solenoid of valve 445 is from the line wire 371 through the conductor 386, contacts 388 and 390, conductors 399 and 405 to the movable contact 452, and from the stationary contact 454 through the conductors 455 and 456 to one end of said right hand winding in the valve 445 and from the other end of said winding through the conductors 446, 439, 431 and 395 to the other line wire 370.

At the same time that the right hand winding of the solenoid valve 445 is energized, the right hand winding of the solenoid valve 412 is energized, this connecting the compressed air line 416 with the conduit 297, which will cause the piston in the cylinder 295 to move to the right as viewed in FIG. 36, which causes the rack 291 to move to the right and rotate the gear 290 in a counter-clockwise direction as viewed in FIG. 9, restoring the parts for another feeding operation for the tie member 263 onto the slide 257, the ratchet mechanism preventing rotation of the knurled surfaced drums 344 along with the gears in this direction. The circuit that includes the right hand winding of the solenoid valve 412 is from the line wire 371 through the conductor 386, contacts 388 and 390, conductors 399 and 405 to movable contact 452 and from the stationary contact 454 through the conduc-

tors 455 and 457 to one end of the winding 425 (see FIG. 35) and from the other end of said winding through the conductors 437, 430, 431 and 395 to the other line wire 370.

The movable contact 392, which is mounted on a spring mounting member 458 that normally holds said movable contact in engagement with the stationary contact 393, is moved out of engagement with the stationary contact 393 when the cam projection 357 engages the roller 369 associated with the operating member for the switch that has this movable contact member 392. Opening of this switch breaks the holding circuit for the relay 373, returning the switch having the contact members 387 and 388 to the position shown in FIG. 36. Upon opening of the circuits controlled by said movable contacts 388 and 387, the switch having the movable contact 382 having been reopened prior to this, will result in the de-energization of the winding in the solenoid valve 377. This causes the air under pressure to be discharged from the clamping jaws 222 and 223 of the twisting member 208, restoring the same to the position thereof shown in FIGS. 15 and 16 ready to receive an extended portion 95 of a bread wrapper from the guide members 147 and 148, the jaws of the twisting member 208 having been aligned with said guides 147 and 148 due to the locking action of the projection 339 on the finger 236.

The movement of the pusher bars 332 is timed with respect to the movement of the pusher members 35 so that the loaf that has been wrapped, except for the extending portion 95 of the wrapper, is delivered to the table 248 immediately after a loaf 64, that has had the open end of the wrapper thereof twisted and tied, is moved away from the position shown in FIG. 11 in dotted lines. Furthermore the rate of travel of the member 332 is such that all of the various operations carried out by the cam mechanism controlling the sequence of operations takes place in a period somewhat shorter than that required for one of the pusher members 332 to move through half its entire path of movement across and back under the table 248.

After the wrapper applied to the loaf 64 has been folded and sealed at one end thereof and overlapped and sealed on the bottom thereof and the open end 95 of said wrapper has passed along between the guide members 122, 140, 145, 147 and the guide members 131, 141, 146 and 148 into engagement with the aligning rollers 153 and 154, and the feeding means 190, 191, 157 and 158, by the pusher members 35, into the position shown in dotted lines in FIG. 11, the extended portion of the wrapper 95, which has been gathered into a flattened tubular form, has reached the position between the clamping jaws 222 and 223 of the twisting member 208 shown thereon in FIGS. 15 and 16. The placing of the loaf in this position closes the switch 250. The cam shaft 354, being rotated continuously, the cam 358 will have to travel a distance dependent upon its position at that time with respect to the roller 369 with which it engages before the switch having the movable contact 382 is closed to start the sequence of operations that is involved in the twisting of the wrapper and the tying of the twisted wrapper. The movable contact members 382, 406, 432, 441, 448 and 452 will close in succession and will reopen as soon as the cam projection engaging the operating member 369 of each of said switches moves past its operating member 369. The normally closed switch having the movable contact 392 will next be opened by engagement of its cam member 357 with its operating member 369.

The relay 373, having been energized by closure of the switch having the movable contact 382, the solenoid valve 377 will move to a position to supply air under pressure to the inflatable clamping jaws 222 and 223, clamping the extended end 95 of the wrapper as shown in FIGS. 17 and 18. The closing of the circuit controlled by the movable contact member 406 will then operate

the solenoid valves 412 and 413, the closing of the solenoid valve 413 causing the holding means for the clutch mechanism to be released to rotate the shaft 206 one revolution and the wrapper twisting member 208 the number of turns desired and at the same time the solenoid valve 412 will supply air under pressure to the cylinder 295 to move the piston in said cylinder to the left to rotate the gear 290 clockwise and feed the tie member 263 into position on the supporting surfaces 262 of the slide 257.

Next the contact member 432 closes the circuit to the left hand winding of the solenoid valve 436, causing air under pressure to be supplied to the cylinder 254 to move the piston therein to the right as viewed in FIG. 36, or upwardly as shown in FIGS. 29 and 30, moving the slide 257 from the position shown in FIG. 29 to that shown in FIG. 30, and during such movement cutting off the length of tie member 263 required for tying the twisted end 251 of the wrapper and bowing the twisted end of the wrapper up into the position shown in FIG. 33. The contact member 441 next moves into circuit closing position and the left hand winding of the solenoid valve 445 is energized, supplying air under pressure to the left hand end of the cylinder 311, causing the tie twisting member having the twisting members 315 to rotate in a counter-clockwise direction, as viewed in FIG. 37, to twist the tie member as shown in FIG. 25.

The wrapper twisting and tying has now been completed, but in order to restore the parts to starting position and permit the removal of the loaf from its twisting and tying station, the contact 448 closes a circuit that energizes the right hand winding of the solenoid valve 436, which supplies air under pressure to the cylinder 254 to restore the slide 257 to the position shown in FIG. 29, whereupon the twisted wrapper portion with the tie member therearound resumes a substantially horizontal position out of engagement with the tie twisting members 315. Next the contact 452 is moved to circuit closing position, whereupon the right hand windings of the solenoid valves 445 and 412 are energized to supply air under pressure to the cylinders 311 and 295 to move the piston in the cylinder 295 to the right and the piston in the cylinder 311 to the left. This restores the rack of the tie twisting member to its starting position and returns the rack 292 of the tie feeding means to its starting position. Next the movable contact member 392 is moved to open position by action of the cam projection 357 and the relay is de-energized through the opening of the holding circuit for the same, opening the circuit to the solenoid valve 377, releasing the clamping jaws 222 and 223 from the wrapper. Immediately after this has taken place, the pusher bar 332 engages the wrapped loaf 64 and moves it out of the position shown in dotted lines in FIG. 11. Then another loaf is moved into the dotted line position shown in FIG. 11 by the pusher members 35 and the operations above described are repeated.

What we claim is:

1. In a bread loaf packaging machine, means for wrapping a length of wrapping material wider than the length of the loaf around said loaf with the wrapping material extending beyond both ends of said loaf including a loaf supporting member movable between a depressed loaf receiving and an elevated loaf discharging position and loaf conveying means extending lengthwise of said machine from said loaf supporting member in its elevated position, twisting means for said extending wrapping material at the discharge end of said conveying means, an arm mounted for movement with said loaf supporting member and into engagement with an end of said loaf and the wrapping material extending beyond said end of said loaf, and upper and lower guide members extending longitudinally of said machine parallel to said conveying means and having an entrance end

adjacent said arm and said extending wrapping material in the elevated position of said loaf supporting means and an exit end at said twisting means, said guide members receiving said extending wrapping material at said end of said loaf between the same and converging toward said exit end thereof.

2. In a bread loaf packaging machine, means for wrapping a length of wrapping material wider than the length of the loaf around said loaf with the wrapping material extending beyond both ends of said loaf including a loaf supporting member movable between a depressed loaf receiving and an elevated loaf discharging position and loaf conveying means extending lengthwise of said machine from said loaf supporting member in its elevated position, twisting means for said extending wrapping material at the discharge end of said conveying means, an arm mounted for movement with said loaf supporting member and into engagement with an end of said loaf and the wrapping material extending beyond said end of said loaf, upper and lower guides extending longitudinally of said machine parallel to said conveying means and having an entrance end adjacent said arm and said extending wrapping material in the elevated position of said loaf supporting means and an exit end at said twisting means, said guides receiving said extending wrapping material at said end of said loaf between the same and converging toward said exit end thereof, a plurality of guide members extending parallel to said guides in laterally outwardly spaced relation thereto, and means for aligning said extending wrapping material longitudinally with said loaf adjacent the exit end of said guide members comprising grooved friction rollers cooperating with said guide members driven at a higher peripheral speed than the speed of said loaf conveying means.

3. In a bread loaf packaging machine, means for wrapping a length of wrapping material wider than the length of the loaf around said loaf with the wrapping material extending beyond both ends of said loaf including a loaf supporting member movable between a depressed loaf receiving and an elevated loaf discharging position and loaf conveying means extending lengthwise of said machine from said loaf supporting member in its elevated position, twisting means for said extending wrapping material at the discharge end of said conveying means, an arm mounted for movement with said loaf supporting member and into engagement with an end of said loaf and the wrapping material extending beyond said end of said loaf, upper and lower guide members extending longitudinally of said machine parallel to said conveying means and having an entrance end adjacent said arm and said extending wrapping material in the elevated position of said loaf supporting means and an exit end at said twisting means, said guide members receiving said extending wrapping material at said end of said loaf between the same and converging toward said exit end thereof, means for aligning said extending wrapping material longitudinally with said loaf adjacent the exit end of said guide members and feed rollers between said wrapping material aligning means and said twisting means.

4. In a bread loaf packaging machine, a table, means for depositing on said table at a predetermined location a wrapped bread loaf having a wrapper portion extending in open ended flattened tubular form endwise from one end thereof, twisting means for said extending portion comprising a pair of elongated jaws provided with clamping means thereon receiving said extending wrapper portion between them, with said jaws extending transversely of said extending wrapper portion, means for mounting said jaws for rotation about an axis extending transversely thereto midway of the length thereof, means for successively closing said clamping means to grip said wrapper portion and rotating said jaws about said axis a predetermined number of turns, and means between said jaws and said table for applying a ductile tie member to said twisted wrapping material adjacent said loaf, comprising

means movable after rotation of said jaws has halted to move a tie member upwardly from a position in which said tie member extends transversely under said twisted wrapping material into engagement with the under side of said twisted wrapping material and bending said tie member around said twisted wrapping material into a U-form with upstanding leg portions extending upwardly from said twisted wrapping material and means for twisting said upstanding legs of said tie member about each other.

5. In a bread loaf packaging machine, a table means for depositing on said table at a predetermined location a wrapped bread loaf having a wrapper portion extending in open ended flattened tubular form endwise from one end thereof, twisting means for said extending portion comprising a pair of elongated jaws provided with clamping means thereon receiving said extending wrapper portion between them, with said jaws extending transversely of said extending wrapper portion, means for mounting said jaws for rotation about an axis extending transversely thereto midway of the length thereof, means for successively closing said clamping means to grip said wrapper portion and rotating said jaws about said axis a predetermined number of turns, and means between said jaws and said table for applying a ductile tie member to said twisted wrapping material adjacent said loaf, comprising a pair of longitudinally spaced tie supporting members having a gap between the same vertically aligned with said axis movable between a lower position below said axis to an upper position above said axis, means for feeding tie material onto said supporting members to extend across said gap, means for cutting off a length of said tie material upon movement of said supporting members upwardly from said lower position, means for moving said supporting members upwardly into said upper position after rotation of said jaws has halted, tie twisting means mounted above said upper position of said supporting members in vertical alignment with said gap for rotation about a vertical axis and means for rotating said tie twisting means about said axis.

6. In a bread loaf packaging machine, a table, means for depositing on said table at a predetermined location a wrapped bread loaf having a wrapper portion extending in open ended flattened tubular form endwise from one end thereof, twisting means for said extending portion comprising a pair of elongated jaws provided with clamping means thereon receiving said extending wrapper portion between them, with said jaws extending transversely of said extending wrapper portion, means for mounting said jaws for rotation about an axis extending transversely thereto midway of the length thereof, means for successively closing said clamping means to grip said wrapper portion and rotating said jaws about said axis a predetermined number of turns, and means between said jaws and said table for applying a ductile tie member to said twisted wrapping material adjacent said loaf, comprising a pair of longitudinally spaced tie supporting members having a gap between the same vertically aligned with said axis movable between a lower position below said axis to an upper position above said axis, means for feeding said tie member onto said supporting members to extend across said gap and cutting off a length thereof, means for moving said supporting members upwardly into said upper position after rotation of said jaws has halted, tie twisting means mounted above said upper position of said supporting members in vertical alignment with said gap for rotation about a vertical axis comprising a pair of twisting fingers extending upwardly and outwardly from said axis and means for rotating said tie twisting means about said axis after said tie supporting members have reached their upper position.

7. In a bread loaf packaging machine, a table, means for depositing on said table at a predetermined location a wrapped bread loaf having a wrapper portion extending in open ended flattened tubular form endwise from one end thereof, twisting means for said extending por-

tion comprising a pair of elongated jaws provided with clamping means thereon receiving said extending wrapper portion between them, with said jaws extending transversely of said extending wrapper portion, means for mounting said jaws for rotation about an axis extending transversely thereto midway of the length thereof, means for successively closing said clamping means to grip said wrapper portion and rotating said jaws about said axis a predetermined number of turns, and means between said jaws and said table for applying a ductile tie member to said twisted wrapping material adjacent said loaf, comprising means movable after rotation of said jaws has halted to move a tie member upwardly from a position in which said tie member extends transversely under said twisted wrapping material into engagement with the under side of said twisted wrapping material and bending said tie member around said twisted wrapping material into a U-form with upstanding leg portions extending upwardly from said twisted wrapping material, means for twisting said upstanding legs of said tie member about each other, and a conveyor comprising transverse pusher bars operating over said table and engaging said loaf to move said loaf from said location off said table after the legs of said tie member have been twisted.

8. In a bread loaf packaging machine, a table, means for depositing in a predetermined location on said table a wrapped bread loaf having a portion of the wrapper extended in open ended flattened tubular form endwise therefrom, twisting means for said extended portion of said wrapper, means for applying a tie to the twisted wrapper after said twisting means has completed the twisting thereof, and means for controlling the sequence of operations of said twisting means and tie applying means, comprising a plurality of circuit controlling cams, a continuously rotating cam shaft and means for supplying electrical energy to the circuits controlled by said cams, comprising switching means engaged by said wrapped loaf upon reaching said location on said table and switching means actuated by one of said cams.

9. In a bread loaf packaging machine, means for wrapping a length of wrapping material wider than the length of the loaf around a loaf with the ends of said material overlapping under said loaf and with the overlapped wrapping material extending beyond both ends of said loaf, means for folding the extended wrapping material at one end of said loaf against said end of said loaf, means for sealing said folded wrapping material and said overlapping ends thereof under said loaf, means for gathering together and twisting on itself the extended wrapping material at the other end of said loaf, comprising twisting means, spaced guiding means converging toward said twisting means, means for directing said extended wrapping material at the other end of said loaf between said guiding means and means for relatively moving said loaf and said guiding means to engage said extended wrapping material with successive portions of said guiding means in the direction of convergence thereof, means for bending a tie member in U-form around said twisted wrapping material adjacent said other end of said loaf and twisting the legs of said tie member about each other.

10. In a bread loaf packaging machine, means for wrapping a length of wrapping material around a loaf with the ends of said length overlapping under said loaf and with the overlapped wrapping material extending beyond both ends of said loaf, said wrapping means comprising means for folding the extended wrapping material at one end of the loaf, means for sealing said folded wrapping material, means spaced from said sealing means for contracting the extended portion of the wrapping material at the other end of said loaf and forming an elongated neck thereof and applying a tie member thereto, means for conveying said loaf from said sealing means to said contracting and applying means, and abutment means cooperating with said conveying means and extending lengthwise of said conveying means to contact and position the folded sealed end of said package, and guide means extending lengthwise of said conveying means and having a guiding surface facing the abutment means in position to abut a portion of the wrapping material at the other end of said loaf and confine said loaf between the abutment means and said guiding surface while permitting the extended portion of the wrapping material to project outwardly beyond the other end of the loaf beyond said surface of the guide means.

11. In a bread loaf packaging machine, means for wrapping a length of wrapping material around a loaf with the ends of said length overlapping under said loaf and with the overlapped wrapping material extending beyond both ends of said loaf, including conveying means for moving the loaf and length of wrapping material along a given path, abutment means extending lengthwise of the conveying means along one side thereof, said abutment means including means for folding the extended wrapping material at one end of the loaf and for sealing said folded wrapping material, guide means extending along the other side of said conveying means and having a guiding surface facing the abutment means in position to abut a portion of the wrapping material at the other end of said loaf and confine said loaf between the abutment means and guiding surface while permitting the extended portion of the wrapping material to project outwardly beyond the other end of the loaf beyond said guiding surface of the guide means, and means adjacent the discharge end of the conveying means for contracting the extended portion of the wrapping material at the other end of said loaf and forming an elongated neck thereof and applying a tie member thereto.
